(57) **CLAIM**

The ornamental design of a combination food jar with
detachable cup, as shown and described.

DESCRIPTION

FIG. 1 is a perspective view from the bottom and one side of
my combination food jar with detachable cup design;
FIG. 2 is a perspective view from the top and an opposite
side of my combination food jar with detachable cup design;
FIG. 3 is a side elevation of my combination food jar with
detachable cup design, it being understood that a side
elevation of the opposite side is a mirror image of this FIG.
3;

FIG. 4 is a front elevation of my combination food jar with
detachable cup design;

FIG. 5 is a side elevation of my combination food jar with
detachable cup design;

FIG. 6 is a bottom plan view of my combination food jar
with detachable cup design; and,

FIG. 7 is a top plan view of my combination food jar with
detachable cup design.
